[57] **CLAIM**

The ornamental design for a belt, as shown and described.

DESCRIPTION

FIG. 1 is a perspective view of a belt showing our new design in a looped and fastened condition;

FIG. 2 is a reduced scale end elevational view of the belt in an open condition;

FIG. 3 is an end elevational view taken from the end opposite that in FIG. 2, and to the same scale;

FIG. 4 is a front elevational view, to the same scale as FIGS. 2 and 3;

FIG. 5 is a rear elevational view, to the same scale as FIGS. 2-4; and,

FIG. 6 is a top plan view, to the same scale as FIGS. 2-5.

The broken line showings of patterns on the medallions are for illustrative purposes only and form no part of the claimed design.
